United States Patent

Des. 238,538
Patented Jan. 27, 1976

238,538

FLOOR MAT

Waldo W. Smith, Warwick, R.I., assignor to Teknor
Apex Company, Pawtucket, R.I.

Filed Apr. 28, 1975, Ser. No. 572,318

Term of patent 14 years

Int. Cl. D6—11

U.S. Cl. D6—226

FIG. 1

FIG. 2

FIG. 4

FIG. 3

FIG. 6

FIG. 5

FIG. 1 is a top plan view of a floor mat showing my new design;

FIG. 2 is a side elevational view thereof;

FIG. 3 is an enlarged fragmentary top plan view of a corner thereof;

FIG. 4 is a bottom plan view thereof of FIG. 3;

FIG. 5 is a cross-sectional view thereof taken on line 5-5 of FIG. 3; and

FIG. 6 is a cross-sectional view thereof taken on line 6-6 of FIG. 3.

I claim:

The ornamental design for a floor mat, as shown and described.
